UNITED STATES PATENT OFFICE.

HENRY M. BEECHER, OF NEW HAVEN, CONNECTICUT.

DESIGN FOR A CARRIAGE-STEP PAD.

SPECIFICATION forming part of Design No. 12,079, dated December 28, 1880.

Application filed August 16, 1880. Term of patent 7 years.

To all whom it may concern:

Be it known that I, HENRY M. BEECHER, of New Haven, in the county of New Haven and State of Connecticut, have invented and produced a new and original Design for Carriage-Step Pads, of which the following is a specification, reference being had to the accompanying drawings, forming part thereof, in which—

10 Figure 1 is a side elevation or edge view of my newly-designed step-pad, and Fig. 2 is a plan view of the same.

Carriage-step pads have been heretofore made with a corrugated or wrinkled surface. 15 They have also been embossed with various figures which covered a part of the surface, while other parts were plain, and a rubber pad for covering an iron step has been made with its upper surface covered by a series of 20 square pyramidal projections having right-angular corners, while the opposite side of the pad was plain. A prior patent also shows a design for stair-plates having the same square pyramidal projections with intersecting ribs 25 upon its upper surface and the under surface of the converse form.

The leading feature of my design consists in ornamenting the upper surface of the step-pad by covering it with adjoining series of 30 diamond-shaped pyramidal projections. I also form the under surface of the said pad the con-

verse of the upper surface—that is, with adjoining series of diamond-shaped pyramidal depressions which substantially cover said under surface.

A represents the step-pad; B, the ordinary shank thereof. The upper surface of the pad is in the form of adjoining series *a a a a a a a* of diamond-shaped pyramidal projections, as shown in Figs. 1 and 2. The under surface is ³⁵ ₄₀ of the converse form, except such portion as is occupied by the end of the shank B.

In some cases, in the practical manufacture of steps all of the pyramidal projections may not be perfectly formed and will appear truncated; but I desire to have each projection come practically to a point.

I claim—

1. The design for a carriage-step pad herein shown and described, in which the upper surface is ornamented by and consists of adjoining series of diamond-shaped pyramidal projections.

2. The design for a carriage-step pad herein shown and described, in which the upper surface consists of adjoining series of diamond-shaped pyramidal projections and the under surface is of the converse form.

HENRY MOSES BEECHER.
